UNITED STATES PATENT OFFICE.

WILHELM REIMERS, OF KIEL, GERMANY.

EXPANSIBLE PULLEY.

1,144,381.

Specification of Letters Patent. Patented June 29, 1915.

Application filed February 18, 1914. Serial No. 819,429.

To all whom it may concern:

Be it known that I, WILHELM REIMERS, subject of the Emperor of Germany, residing at Klinke 7-9, Kiel, in the Empire of Germany, have invented new and useful Improvements in Expansible Pulleys, of which the following is a specification.

The present invention relates to improvements in expanding pulleys formed of one or more superimposed spirally wound spring-strips held in the form of a closed rim and capable of being expanded at will by a centering device.

The improvements consist in new and improved means for expanding and contracting the outer diameter of the pulley face formed by the spring-strips.

In the accompanying drawing, Figure 1 is an elevation partly in section of one form 20 of construction of the improved pulley. Fig. 2 is a vertical section of same.

In the form shown in Figs. 1 and 2, the rim of the pulley consists of three spring-strips 1, 2, 3 arranged and guided between the side-walls 4 and 5 of the pulley which are connected by the hub 6 on the shaft. The side-walls 4 and 5 have slots 7 which serve as guides for bridge members a^1 , a^2 , a^3 . On each of these members are fastened transversally one end (which may be named outer end) of each of the spring-strips. The outer ends of the strips 3, 2 and 1 are fastened on the members a^1 , a^2 and a^3 respectively. In the bridge-members are journaled shafts b carrying at their ends spur wheels c^1 and c^2 intermeshing with the racks d^1 , d^2 fastened on either walls 4 and 5. On each shaft b is moreover keyed a worm-gear e intermeshing with the worm-shafts f suitably journaled on the wall 5 and rotated in one or the other direction by bevel-gears 8 and 9 from the brake-pulleys g^1 and g^2 respectively. By thus turning the worm-shafts f the bridge-members a^1 , a^2 , a^3 and

the ends of the spring-strips fastened thereon are drawn into the slots 7. The other ends of the spring-strips (which may be called the inner ends) are fastened on the semicircular parts i^1 , i^2 , i^3 provided at their concave faces with teeth to engage with gears h on the said shafts b and moving in guides j formed in the bridge-members a^1 , a^2 , a^3 . It is apparent that by turning the shafts b , the outer ends of the spring-strips are drawn inward toward the center of the pulley while their inner ends are wound spirally and inwardly.

I claim:—

In an expansible pulley of the character described, the combination of an expansible rim, consisting of spring-strips, members to which the outer ends of said strips are secured, side walls for the pulley provided with slots for guiding said members, a hub to which said side walls are secured, shafts journaled in said members, spur-wheels at the ends of said shafts, racks secured to both of said side walls intermeshing with said spur-wheels, a worm gear keyed to each of said shafts, worm-shafts journaled in one of the said side walls, means for rotating said worm shafts in both directions for drawing the ends of the strips into the slots of said side walls, segments moving in guides formed upon said members to which the inner ends of said strips are secured, provided at their concave faces with teeth, and gears on the shafts journaled in said members, meshing with said teeth, substantially as described and for the purpose set forth.

In testimony whereof I affix my signature in presence of two witnesses.

WILHELM REIMERS.

Witnesses:

WOLDEMAR HAUPT,
HENRY HASPER.
